UNITED STATES PATENT OFFICE.

JOHN PHELAN, OF PITTSBURG, PENNSYLVANIA, ASSIGNOR OF ONE-HALF
TO RALPH J. RICHARDSON, OF SAME PLACE.

MACHINE-GUN.

SPECIFICATION forming part of Letters Patent No. 249,204, dated November 8, 1881.

Application filed June 23, 1881. (No model.)

To all whom it may concern:

Be it known that I, JOHN PHELAN, of Pittsburgh, in the county of Allegheny and State of Pennsylvania, have invented a new and useful Improvement in Machine-Guns; and I do hereby declare that the following is a full, clear, and exact description thereof, reference being had to the accompanying drawings, and to the letters of reference marked thereon.

10 My invention relates to an improvement in machine-guns; and it consists in the combination of a series of guns so arranged with relation to each other that they may be continuously loaded and simultaneously pointed in different directions and discharged consecutively, the operating mechanism of the several guns being coupled together, so that one person may operate all of the guns constituting the battery, the whole being constructed, arranged, 20 and operating in the manner as will herein-after more fully appear.

To enable others skilled in the art with which my invention is most nearly connected to make and use it, I will proceed to describe its construction and operation.

In the accompanying drawings, which form part of my specification, Figure 1 is a top view or plan of my improvement in battery for military purposes. Fig. 2 is a rear or end elevation of the same. Fig. 3 is a vertical and longitudinal section of the same at line $y\ y$ of Fig. 1. Fig. 4 is a side elevation of the battery. Figs. 5 and 6 are horizontal sections at lines $y'\ y'$ and $y''\ y''$ of Fig. 4. Figs. 7, 8, and 9 are detail views.

Reference being had to the accompanying drawings, A represents the carriage or support for the several guns constituting the battery.

40 B B B represent the guns, which at the breech are secured in and to swivel-stands C C C. The upper half, a , of the breech is attached to a yoke, D, having trunnions bb , which move in curved slots cc in the arms E, which 45 project from the swivel-stands C. On the inner sides, at the ends of the projecting arms E, are guide-pieces d , (see Figs. 3 and 4,) between which the projections e on the side of the hopper F move, the lower end of the hopper rest-

ing on the upper half, a , of the breech of the 50 gun. The hopper F has a slide-bottom, f , which is operated by arms g , attached to the yoke D. The front and rear walls of the hopper are about vertical; but the side walls, h , converge toward the bottom, so that the openings in the 55 bottom are about the width and length of the cartridge for the gun. The upper half, a , of the breech on its upper side is slightly curved longitudinally, which imparts to the hopper F by the back-and-forward movement of the upper half, a , of the breech and the yoke D, a slight vertical movement.

Just below the part a of the breech and to the front part of the yoke D are pivoted fingers i , for withdrawing the shell of the cartridge 65 after the gun has been fired; and just below these fingers is pivoted the hammer G, operated by the spring j , and grooved eccentric H, pivoted in and between the projecting arms E, the projection k of the hammer G moving in 70 the groove l of the eccentric H, and thrown out of said groove when the projection m of the eccentric comes in contact with the projection k . The several eccentrics H are coupled together by means of swivel and sliding couplings n , 75 and the swivel-stands C C C are coupled by means of links I J K, and to link J is connected an operating-lever, L.

The skillful mechanic from the foregoing description, and by reference to the accompanying drawings, will readily understand the construction of the several parts and the relation they bear to each other. I will therefore proceed to describe the operation, which is as follows: The hoppers F being charged with cartridges, the operator, by means of a crank, A', rotates the couplings n , which revolve the eccentrics H, which moves forward the yoke D, arms g , and sliding bottom f , which will allow a cartridge to drop down on the top side of the 80 upper part, a , of the breech. The eccentric H then moves backward the yoke D, carrying with it the upper part, a , of the breech. The cartridge will be allowed by the receding of the part a to drop down into its chamber in the 85 breech of the gun B, as shown in Figs. 3 and 5. The eccentric then moves forward the yoke D, which will bring the part a of the upper

part of the breech into place over the breech, in which position the gun is charged with a cartridge and ready to be discharged, with another cartridge resting on the upper side of the 5 upper part, *a*, of the breech. The projection *m* of the eccentric *H* then acting against the projection *k* of the hammer *G*, pulls it back until the projection *m* passes the projection *k*. The spring *j* then causes the hammer *G* to 10 strike the end of the shell of the cartridge, and thereby explode it. The forward ends of the fingers *i*, having caught over the flange of the shell of the cartridge, as shown in Fig. 5, the backward movement of the yoke *D* will draw 15 back the fingers *i*, which will draw back the cartridge-shell, and the rear ends of the fingers *i* will strike against the inclines *p* on the inner sides of the projecting arms *E*, and thereby spread the front ends of the fingers *i*, as shown 20 in Fig. 6, and allow the cartridge-shell to drop from the gun and another cartridge to drop into the breech of the gun, to be exploded in the manner hereinbefore described. The guns are pointed in different directions by moving 25 the lever *L* from right to left.

By the peculiar construction of the battery hereinbefore described a continuous discharge of shot may be had with a scattering of shot in various directions by a single gunner.

Having thus described my improvement, 30 what I claim as of my invention is—

1. The combination of machine-guns separately mounted on swiveled carriages, a shaft with swiveled couplings operating all the guns, and mechanism, as described, for training the 35 guns in different directions while operating them simultaneously, substantially as specified.

2. The combination, with the hopper *F* and the upper part, *a*, of the breech of the gun, of 40 the sliding bottom, *f*, arm *g*, and yoke and eccentric *D H*, whereby said parts *a f* are adapted to be moved back and forth, substantially as and for the purpose specified.

3. The combination, with the series of guns 45 *B*, having hoppers *F*, provided with sliding bottoms *f*, of the yokes *D*, having the upper portions, *a*, of the breeches of the guns attached thereto, the hammers *G*, fingers *i*, and grooved eccentrics *H*, connected by swivel-couplings, 50 and provided with lugs *m*, substantially as and for the purpose herein shown and described.

JOHN PHELAN.
